DUAL PRODUCTION ZONE PUMP

Charles A. Morris and John D. Exner, Wichita Falls, Tex., assignors, by mesne assignments, to Standard Oil Development Company, Elizabeth, N. J., a corporation of Delaware

Application April 27, 1950, Serial No. 158,368

3 Claims. (Cl. 103—4)

1

The present invention relates to deep well pumps of the reciprocating type. More particularly the invention relates to an improved combination of elements forming a unitary pump capable of pumping fluids simultaneously from spaced, subsurface formations while maintaining the pumped fluids segregated from each other.

It is known to pump fluids, such as oil or water, from spaced producing formations either by employing a plurality of single zone pumps arranged in a plurality of different boreholes or by employing a unitary structure employing a plurality of pumps in a single borehole with each pump withdrawing fluid from a different subsurface formation. Ordinarily it is impractical to pump fluid from more than two pay zones by means of a single unitary pump structure.

Deep-well, dual-zone pump structures of the prior art have suffered from the disadvantages of being constructed in such fashion that, if, after installation in a well, it becomes necessary to service the lower zone pump, the entire structure, including the production tubing string, must be withdrawn from the well; or the pump structure has included a complicated and expensive packing arrangement for isolating the internal operating zones of the pumps.

It is one object of the present invention to provide, in a unitary structure, an improved deep-well pump adapted to pump fluids simultaneously from two, spaced subsurface formations without admixing the fluids pumped from the two formations.

It is another object of the present invention to provide a dual-zone pump structure so constructed and arranged that the traveling elements of both pumps may be withdrawn from the well for servicing without disturbing the tubing string on which the pump structure is normally suspended in the well.

It is a further object of the present invention to provide a simple and inexpensive means for sealing the internal operating zones between two reciprocating pumps aligned in a unitary, deep-well pump assembly.

Still other and further objects of the present invention will become apparent from the following description taken in conjunction with the accompanying drawings in which:

Fig. 1 is an elevation view, partly in section, of the upper portion of one embodiment of a dual-zone pump assembly constructed in accordance with our invention, and showing an upper production zone pump;

Fig. 2 is an elevation view, partly in section, of

2

a next lower intermediate portion of the embodiment shown in Fig. 1 and showing a seal barrel and plunger in accordance with our invention for sealing the internal operating zones between pumps;

Fig. 3 is an elevation view, partly in section, of a still lower intermediate portion of the embodiment illustrated in Figs. 1 and 2, and showing a casing-tubing packer for sealing between two producing formations;

Fig. 4 is an elevation view, partly in section, of the lower portion of the embodiment shown in Figs. 1, 2 and 3, and showing particularly a lower production zone pump; and

Fig. 5 is a cross-sectional view taken along the line V—V of Fig. 1.

In the several views, like numerals refer to like parts of the assembly.

In the drawing, the numeral 11 designates the walls of a borehole which penetrates subsurface earth formations including two producing formations or zones, such as an upper zone 12 (Fig. 1) and a lower zone 13 (Fig. 4). In usual practice, the borehole will be cased by a casing string 14 which is supported at the well head (not shown) in conventional manner, extends below the upper producing formation 12, and is cemented in place adjacent the lower end of the casing as by cement plug 15. Opposite the upper producing formation 12, casing 14 is perforated, as by means of perforations 16. Within casing 14 is a stationary, production tubing string 17 which, similar to casing 14, is supported in the well head in conventional manner.

In accordance with a preferred embodiment of our invention, a tubular head member or sub 18, provided with a central longitudinal passage 19, is screw-threadedly engaged to the lower end of tubing string 17. The lower end of head member

18 has a substantially larger outside diameter than tubing string 17 and is threadedly secured to the upper end of a first, or upper, tubular jacket 20, which also is of larger diameter than tubing 17. Jacket 20 is constructed of sufficient length to house an upper production zone pump which will be described more fully hereinafter.

Screw-threadedly engaged to the lower end of jacket 20 is a first coupling member 21 which, as will become apparent from subsequent description, serves also as an anchor member for the upper zone pump. Depending from, and screw-threadedly engaged to, the lower end of member 21 is a second, or intermediate tubular jacket 22 which is preferably constructed similar to jacket 20 but of sufficient length to house a

seal barrel which will be subsequently described. At the lower end of jacket 22, a second coupling member or sub 23 is screw-threadedly engaged thereon. Coupling member 23 is provided with a central longitudinal passage 24 and, preferably, is tapered at its lower end to a smaller external diameter than jacket 22. Secured to the lower end of member 23, as by screw threads, is a third, or lower, tubular jacket 25 which terminates in a conventional bottom-lock releasable pump hold-down device 26 provided with a longitudinal fluid passage 27 such, for example, as the pump anchor shown and described in the Kelly et al. Patent, 2,298,567. Tubular jacket 25 is constructed at least of sufficient length to house a lower zone pump, which will be described hereinafter, and will preferably terminate adjacent or below lower producing formation 13. If desired, any suitable form of well screen or mud anchor may be secured to the lower end of pump anchor 26. In the drawing, a perforated tubing nipple 28 has been shown to represent such a means for admitting lower zone fluid.

It will be understood that jackets 20, 22, and 25 may be constructed of convenient lengths of suitable diameter tubing coupled together at intermediate points, as needed, by conventional collars not specifically pointed out hereinabove. Although, for convenience in description, members 20, 22 and 25 have been described as three different jackets, it will be apparent that these members are so joined together that they may also be considered as forming a single jacket assembly for a unitary structure. While the members 22, 23, and 25 form parts of a single jacket assembly, upon consideration it may be seen that these members, in combination with the pump anchor 26, also serve as means for supporting the lower pump at a selected distance below the upper pump. As may be seen from the drawing, all of these members are aligned along a common central axis.

Around the jacket structure, at a position between producing formations 12 and 13, and preferably within casing 14, there is disposed a conventional packer means 29, as shown in Figure 3. Although a cup-type casing-tubing packer has been illustrated in the drawing, it will be understood that packer means 29 may be any suitable packer adapted to seal between the jacket and the casing 14, or between the jacket and the walls of an uncased borehole intermediate between producing formations 12 and 13 to prevent intermixing of formation fluids external to the pump assembly.

Secured to pump anchor 26, as by means of pull tube 30 and collar 31, is a lower tubular plunger 32 provided with suitable circumferential packing rings, or cups, 33 and a conventional standing valve means 34. Reciprocatably sliding over plunger 32 and packing means 33, is a lower pump traveling barrel 35 provided at its upper end with a conventional traveling valve means 36 and open valve cage 37. Secured to the lower end of barrel 35 and concentrically around pull tube 30 is a sleeve or bushing 38, adapted to engage against collar 31 during an extreme upward pull transmitted to barrel 35 when it is desired to release hold-down means 26 from its anchored position and thereby remove plunger 32 from its normal operating position. Since the structure and the operation of a suitable pump anchor 26 is well known in the prior art, further description thereof is omitted herein.

From the foregoing description it may be seen

that the working barrel 35 and its associated traveling valve structure 36, 37 form a cylindrical reciprocating element in the lower pump, while the plunger 32, with associated packing means 33 and standing valve means 34, form a cylindrical stationary element which co-operates with the reciprocating element to pump a fluid. It will be apparent to workers in the art, however, that by suitable rearrangement of the standing and traveling valves, the above-described pump may be inverted so that the working barrel is held stationary by anchor means 26, and the plunger 32 may be caused to reciprocate therein. The plunger will then be the cylindrical reciprocating element in the lower pump.

As may be seen from Fig. 4 of the drawing, an upward stroke of barrel 35 causes lower formation fluid to be drawn through well screen or tubing nipple 28, fluid passage 27, the bore of pull tube 30, the bore of tubular plunger 32, and thence through standing valve means 34 into the interior of barrel 35. When barrel 35 is forced downward, valve means 34 closes, valve means 36 opens, and the fluid within barrel 35 is forced into the bore of tubular jacket 25 above valve 36.

In order to impart longitudinal reciprocating motion to barrel 35, a first sucker rod string 39, arranged substantially concentrically within jacket 25 and the central passage 24 of coupling member 23, is threadedly secured to cage 37 which, in turn, is suitably secured to barrel 35. The upper end of rod string 39 is threadedly secured to the lower end of a valveless blind plunger 40.

Plunger 40 is constructed with a slightly larger outside diameter than the outside diameter of traveling barrel 35, and is provided with suitable circumferential packing rings or cups 41. Plunger 40 and packing means 41 are arranged to reciprocate longitudinally in an elongated tubular seal barrel 42 and, in combination with the latter, to provide an effective, movable seal between the internal operating zones of the lower pump, described hereinabove, and an upper pump, to be described hereinafter.

Seal barrel 42, as may be seen from Figs. 1 and 2, is screw-threadedly secured in the lower portion of central passage 43 in coupling member 21, and is seated, or otherwise suitably retained, in an enlarged upper portion of central passage 24 in coupling member 23. Adjacent to coupling member 23 and the lower end of seal barrel 42, the latter is provided with one or more fluid ports 44 adapted to pass the pumped lower zone fluid from the bore of jacket 25 and central passage 24 into a first annular passage 45 defined between the outer walls of seal barrel 42 and the inner walls of jacket 22. As may be seen from Figs. 1 and 2, annular passage 45 extends throughout the length of jacket 22 between coupling members 21 and 23.

Secured to the upper end of blind plunger 40, as by screw threads or other suitable means, is a second sucker rod string 46 which passes upwardly through central passage 43 in coupling member 21 and terminates in a yoke 47.

In the drawing of Fig. 1, coupling member 21 has been shown in section taken along the section line I—I of Fig. 5. Similarly, in the drawing of Fig. 5, coupling member 21 has been shown as a section taken along the line V—V of Fig. 1. As may be seen from these figures, coupling member 21 is provided with a plurality of bypass passages 48 extending longitudinally there-

through and providing communication between first annular passage 45 and a second annular passage 49 defined between the outer walls of a stationary upper pump working barrel 50 and the inner walls of jacket 20. The lower end of upper pump working barrel 50 is screw-threadedly secured, and thereby anchored, in coupling member 21 in the upper end of central passage 43, while the upper end of said barrel is seated, or otherwise secured, in the central passage 19 of head member 18. One or more fluid re-entry ports 51 are provided adjacent the upper end of working barrel 50 to provide means for passing pumped lower zone fluid out of annular passage 49 into passage 19 and thence into tubing string 17.

The outer walls of coupling member 21 are pierced by a plurality of upper zone fluid entry ports 52 which communicate, through suitable screens 53 and upper pump standing valve means 54, with a plurality of ports 55 entering central passage 43. Thus, upper zone fluid, drawn through perforations 16 in casing string 14, enters ports 52, passes through screens 53 and standing valves 54, and enters central passage 43 through ports 55.

Although, for convenience of description, the member 21 has been termed "a coupling member" by virtue of its utilization to couple jacket members 20 and 22 together, it will be apparent that, since member 21 also carries the standing valves of the upper pump and is screw-threadedly attached to the working barrel or cylinder 50 of this pump, the member 21 and the working barrel 50 together may be jointly described as forming the cylinder structure of the upper pump. When considered thus, the threaded juncture between seal barrel 42 and member 21 provides a means for sealing said seal barrel to said cylinder structure.

Arranged for longitudinal reciprocating movement in working barrel 50 is a movable upper pump plunger 56 provided with circumferential packing rings or cups 57. Plunger 56 is tubular, thereby permitting passage of fluid through central bore 58 therein. At its lower end, plunger 56 is secured to yoke 41, as by suitable screw threads. Ports 59 are provided in yoke 41 so that fluid in the lower part of working barrel 50 may enter bore 58 of plunger 56.

Arranged along bore 58 of plunger 56, and suitably secured therein, is a traveling valve means 60. Secured to the upper end of plunger 56 and above valve means 60, is a bushing 61 which connects the plunger to a movable tubing string 62. Tubing 62 passes upwardly through passage 19 in head member 18, and, thence, substantially concentrically within and through stationary tubing string 17.

The upper end of movable tubing string 62 passes through a conventional stuffing box above the well head and may be connected through a flexible connection to a flow line. Tubing string 62 is also connected for reciprocation to a suitable pump jack. Since the means for drawing fluid from tubing 62 and the means for imparting longitudinal reciprocating movement thereto form no part of the present invention, details of these means are not shown herein. It may be seen, however, that when tubing 62 is moved longitudinally, the resulting reciprocating movement is imparted to pump plunger 56, second sucker rod string 46, blind plunger 40, first sucker rod string 39 and lower pump traveling barrel 35, simultaneously. These elements, taken as a

unit, form a common reciprocating member which is operatively connected to each of two pumps.

In the operation of the pump assembly of our invention, lower zone fluid which has been forced into the bore of lower jacket 25, as has been hereinbefore described, is forced upward through central passage 24 in coupling member 23, through fluid ports 44 in seal barrel 42, and into annular passage 45. Continued operation of the pump assembly forces the fluid in annular passage 45 upward through by-pass passages 48 in coupling member 21, then through the second annular passage 49, fluid re-entry ports 51 in working barrel 50, and thence into stationary production tubing 17. Because of the presence of seal barrel 42, blind plunger 40, therein, upper pump working barrel 50, and upper pump plunger 56, lower zone fluid cannot intermix with fluid drawn into the upper zone pump.

As may be seen from Fig. 1, when plunger 56 is moved upward, upper zone fluid enters through perforations 16, entry ports 52, screens 53, standing valve means 54, ports 55, central passage 43 and into the bore of working barrel 50. Thereafter, when plunger 56 is moved downward, valve means 54 closes, traveling valve means 60 opens and upper zone fluid is forced upward through ports 59, central bore 58, valve means 60 and thence into the bore of tubing 62.

From an examination of Figs. 1 and 2, it may be seen that the upper zone pump operates on the principle of differential displacement of the two plungers, 40 and 56, on opposite sides of a valved, fluid-entry port 55. The bore of working barrel 50 must be greater than the bore of seal barrel 42 in order to obtain fluid delivery from the upper zone pump. By suitable choice of the internal diameters of these barrels, the volumetric delivery of the upper zone pump may be adjusted.

In accordance with one objective of the device of our invention, the bore of tubing string 17 is also constructed of greater diameter than the outside diameter of upper pump plunger 56, the bore of working barrel 50 is of greater diameter than the outside diameter of blind plunger 40, and the bore of central passage 43, seal barrel 42, and central passage 24 are greater than the outside diameter of lower pump traveling barrel 35 so that, when it is desired to service either the upper zone pump traveling elements or the lower zone pump, the movable tubing string 62 may be pulled upward for a greater distance than the normal operating stroke. Thereafter, tubing string 62 may be drawn upward out of the well followed by the other elements including plunger 56, sucker rods 46, blind plunger 40, sucker rods 39, traveling barrel 35, plunger 32, and the releasable portion of pump anchor 26.

It may be seen that, by employing moving blind plunger 40 sealingly reciprocatable in fixed seal barrel 42, expensive and troublesome latching means for retaining inter-pump packing means in position is eliminated and the lower zone pump may be removed from the well without withdrawing the tubing string 17 and the pump jackets depending therefrom.

As will be apparent the lengths of tubing 17, jacket 20, jacket 22, jacket 25, sucker rod string 39, sucker rod string 46, and movable tubing string 62 may be varied to suit the particular depths and spacing of producing formations 12 and 13 beneath the surface of the earth. First

coupling member 21 ordinarily will be installed above packer 29 and below the normal standing level of liquid derived from formation 12, while the lower zone pump, and especially the standing valve therein, will generally be installed below the normal standing level of liquid derived from formation 13.

Although our invention has been described with respect to a single embodiment thereof, it will be understood that modifications and changes may be made without departing from the scope of the appended claims. It is, therefore, to be understood that our invention is not to be limited to the specific details shown and described herein.

Having thus described our invention, what we claim as novel, and desire to secure by Letters Patent, is:

1. A dual zone pump assembly adapted to pump fluid simultaneously from lower and upper sub-surface zones without intermixing the fluid from said zones comprising, in combination, a tubular head member, defining a central passage therethrough, adapted to be threadedly secured to the lower end of a stationary tubing string within a suitably perforated casing string in a borehole; a first tubular jacket threadedly secured independently from said head member; a first coupling member defining a central longitudinal passage and at least one longitudinal by-pass passage therethrough, and also defining an upper zone entry port arranged to provide ingress of fluid from said upper zone into said central passage, said coupling member threadedly joining the upper end of a second tubular jacket collinearly to the lower end of said first jacket; a second coupling member, defining a central longitudinal passage therethrough, threadedly joining the upper end of a third tubular jacket collinearly to the lower end of said second jacket; means adjacent the lower end of said third jacket for admitting fluid from said lower zone into the interior of said third jacket; a releasable lock hold-down means, provided with a longitudinal fluid passage therethrough, positioned within said third jacket and above said fluid admitting means; a lower tubular plunger, provided with suitable circumferential packing rings in the outer walls thereof, secured to said hold-down means coaxially within, and spaced from, said third jacket; a lower pump barrel arranged for reciprocating movement concentrically over said lower plunger; standing valve means in said lower plunger and traveling valve means in said lower pump barrel constructed and arranged to cooperate and deliver fluid above said lower pump barrel upon downward movement of the latter; packer means secured circumferentially around said third jacket below the upper extremity thereof and adapted to seal off an annular space defined between said third jacket and said casing string; a tubular seal barrel, defining at least one fluid port through the wall and adjacent the lower end thereof, seated in the central passage of said second coupling member and threadedly secured in the central passage of said first coupling member whereby an annular passage is provided between said seal barrel and said second jacket; a blind plunger, provided with suitable circumferential packing means slidably engaging inner walls of said seal barrel, arranged for longitudinal reciprocating movement concentrically within said seal barrel; a first sucker rod string securing the lower extremity of said blind plunger to the upper extremity of said lower

pump barrel; a stationary upper pump barrel, defining at least one fluid reentry port adjacent its upper extremity, threadedly secured at its lower end in the central passage of said first coupling member and seated at its upper end in the central passage of said head member whereby an annular passage is provided between said pump barrel and the first tubular jacket; a movable upper pump plunger, defining a central bore and having suitable circumferential packing means in the outer walls thereof slidably engaging inner walls of said upper pump barrel, arranged for reciprocating movement concentrically within said upper pump barrel; standing valve means in the upper zone entry port of said first coupling member and traveling valve means in said upper pump plunger constructed and arranged to cooperate and deliver fluid above said traveling valve upon downward movement of the upper pump plunger; a second sucker rod string securing the upper end of the blind plunger to the lower end of the upper pump plunger; and a movable tubing string adapted to reciprocate substantially concentrically within said stationary tubing string, threadedly secured to said upper pump plunger above the traveling valve means therein.

2. In a dual zone pump assembly adapted to be secured to the lower end of a tubing string in a well having upper and lower fluid-producing zones wherein said pump assembly comprises an elongated jacket assembly carrying an upper reciprocating pump and a lower reciprocating pump therein; and wherein said upper pump includes a cylindrical working barrel secured to the jacket assembly, a valved piston slidably engaging the interior walls of the working barrel, and upper standing valve means carried in fluid-entry ports formed in said jacket assembly below the working barrel and above the lower pump; and wherein said lower pump includes a reciprocating part carrying a traveling valve, a stationary part carrying a lower standing valve, and releasable anchor means for anchoring the stationary part to the lower end of the jacket assembly; the improved means for segregating internal operating zones of said upper and lower pumps which includes an elongated cylindrical seal barrel secured to the jacket assembly below the upper standing valve and above the lower reciprocating pump, said seal barrel having an internal diameter smaller than the external diameter of said valved piston and larger than the external diameter of said lower pump, a blind plunger slidably engaging interior walls of the seal barrel; rod members securing the blind plunger, in suitable spaced relation, to the valved piston in the upper pump and to the reciprocating part in the lower pump; said tubing string, said upper pump working barrel, said seal barrel, and the lower portion of said jacket assembly defining an unimpeded passageway whose internal diameter is proportioned stepwisely smaller in the downward direction whereby said valved piston, blind plunger, and lower reciprocating pump may be withdrawn upwardly from the jacket assembly upon release of the anchor means of the lower pump.

3. A deep-well pump assembly including, in combination, a first reciprocating pump comprising an elongated cylinder structure and a piston slidably engaging interior walls thereof; a second reciprocating pump comprising a cylindrical reciprocating element and a concentric stationary element co-operatively associated therewith

to pump a fluid; means supporting said second pump coaxially at a selected distance below said first pump along a central axis common to both pumps; a rod member secured axially to the lower end of said piston and to the upper end of said cylindrical reciprocating element for transmitting reciprocating movement of the former simultaneously to the latter; an elongated cylindrical seal barrel spaced concentrically around said rod member between said first and second pumps, the internal diameter of said seal barrel being greater than the external diameter of said second pump and less than the internal diameter of said cylinder structure; means sealing the upper end of said seal barrel to the lower end of 15 said cylinder structure; and a blind plunger se-

cured coaxially around said rod member within said seal barrel and slidably engaging interior walls of the latter.

CHARLES A. MORRIS.
JOHN D. EXNER.
